CLAIM

The ornamental design for a shoe, as shown and described.

DESCRIPTION

FIG. 1 is a side view of a shoe showing my new design; FIG. 2 is a rear perspective view thereof; FIG. 3 is a rear view thereof; FIG. 4 is an opposite side rear perspective view thereof; FIG. 5 is an opposite side view thereof; FIG. 6 is a side view of a shoe showing an alternate embodiment of my new design; FIG. 7 is a rear perspective view thereof; FIG. 8 is a rear view thereof; FIG. 9 is an opposite side rear perspective view thereof; and, FIG. 10 is an opposite side view thereof. The broken lines immediately adjacent to the shaded area define the bounds of the claimed design and form no part thereof. The broken lines showing of the race-track shaped elements form no part of the claimed design. In FIGS. 6-10, the oblique shade lines represent a translucent or transparent

appearance. The broken lines depicting the remainder of the shoe form no part of the claimed design.
